APPARATUS FOR CONNECTING
COIL SPRINGS

Julius Spühl, Saint Gallen, Switzerland

Application December 18, 1947, Serial No. 792,538
In Switzerland August 10, 1943Section 1, Public Law 690, August 8, 1946
Patent expires August 10, 1963

3 Claims. (Cl. 140—11)

1

The present invention relates to a method of connecting the end rings of springs to the edge frames of the spring boxes for mattresses and similar upholstered articles, and to an appliance for carrying out the method.

In making the spring-boxes for upholstered articles it is known to connect the end rings of the springs to the edge frames by means of metal clamps which are pushed over the laid-together end windings of the springs and the edge frames and are then closed by means of pliers. Such a connection is not durable, since the sheet-metal clamps cannot be pressed together by hand with sufficient pressure to cause them to lie snugly round the hard spring wire and the edge frame. Besides that, this method of connecting requires much time and is therefore expensive.

According to the method of the present invention, a part of the edge frame and the part of the end ring of a spring to be connected to it, and also a binding wire drawn off piecemeal from a stock supply, are introduced into a winding appliance and then, by operating the winding appliance, the binding wire is wound a few turns round the end ring and the edge frame and severed from the stock.

The device for carrying out the method has a winding appliance for taking a part of the edge frame and the part of the end ring of a spring to be connected to the frame, and also a feed device for a binding wire drawn off piecemeal from a stock supply, means for winding the binding wire round the parts of the edge frame and the spring lying in the winding appliance, and a cutting tool for severing the wound binding wire from the stock.

One form of execution of the appliance according to the invention for carrying out the method is illustrated by way of example in the accompanying drawing, in which:

Figs. 1-3 show front views of the appliance, with some parts broken away,

Figs. 4-7 details of the appliance,

Figs. 8 and 9 variants of the connection and

Fig. 10 shows an upholstered body on a small scale.

The appliance in the drawing has a stand 1 in which a shaft 2 is rotatably supported. The driving shaft 2, which can be set rotating by driving means through a coupling (not illustrated), carries two cams 3 and 4, and also a toothed wheel 5. The toothed wheel 5 is in engagement with a further toothed wheel 6 mounted on an axle 7 fixed in the stand 1. A lever 8, pivoted on a pin 9 and carrying a finger 58

2

10, is actuated by the cam 3. On the periphery of the cam 4 runs a roller 11, mounted on the arm 12 of a bell-crank lever 12, 13 which is supported on the stand 1 so that it can swivel round the axle 14. A torsion spring 15 tends to press the roller 11 against the cam 4, since it tries to turn the bellcrank lever 12, 13, in that sense. At the free end of the arm 13 a knife 16 is fixed, which is hollowed out at 17 above its cutting edge. The knife 16 works in conjunction with a counter-knife 18 fitted on the machine stand 1.

On an axle 19 of the machine stand 1 a three-armed lever 20, 21, 22 is pivoted. To the arm 20 of this lever a slide 23 is linked, which runs on a guide 24 of the stand 1 and has in a projection a hole 25 for letting a wire 26 through. The slide 23 carries a swivelling lever 27 with a weight 28 and a finger 29 lying before the hole 25, and pressing the wire 26 against the flat 25'.

20 The arm 21 carries a roller 30 and a draw-bar 31 which engages with the arm 21 and allows it to be swung away from a stop 32. The roller 30 is adjustable along one arm 33 of a two-armed lever 33, 34 which is pivoted on an axle 35 in the stand 1. A stop 36 on the arm 33 limits the movement of the roller 30. The arm 33 is connected to the arm 22 by means of a tension spring 37. One arm 34 is linked to a slide 38, which is adjustable along a guide 39 and has a notch 40 in its front end.

25 The intermediate toothed wheel 6 is in engagement with a further toothed wheel 41 which is provided with a radial incision 42 (Fig. 7) extending beyond its axis and is pivoted in a bearing 43 (Fig. 2) of the machine stand, this bearing having also a radial incision 44 (Fig. 1). The bearing of the toothed wheel comprises a bush 45 with a longitudinal slot in the neighbourhood of the incision 42 of the toothed wheel 41. At one end this bush 45 has an operating tooth 46 (Fig. 6) projecting in the axial direction.

30 On the machine stand (Figs. 4 and 5) a holder 47 with a notch at its front end is fitted. The clamping plate 48 for the fixed knife 18 has also a notch at its front end. The notches in the parts 47 and 49 lie in one axis and collaborate with the notch 40 in the slide 38. A pawl 50 swings freely on the machine stand over the wire 26 (Fig. 1).

35 The method of working of the described appliance is the following:

The edge frame 51 of the upholstered article (Fig. 10), which is either of rectangular cross-section according to Fig. 8 or of circular cross-section according to Fig. 9, is laid into the notches

of the holder 47 and the part 49, and the part of the end ring of a spring 52 to be connected to this frame is laid on or beside it. The axis of the mentioned notches coincide with the axis of the toothed wheel 41 and of its bearing bush 45, so that the frame 51 and a part of the end ring 52 are located at the bottom of the radial incision 42 through which they have been passed into the notches.

Now in the first working operation, when the draw-bar 31 is pulled downwards by means of a pedal for instance, the three-armed lever 20, 21, 22 swivels round the pin 19. The slide 23 is then pushed on the guide 24 out of the position shown in Fig. 1 into that shown in Fig. 2, the wire 26 being held by the clamping between the finger 28, the flat 25' and the hole 25, and therefore pushed forwards. At the same time the roller 30 on the arm 21 runs along the arm 33 and swivels the two-armed lever 33, 34 about the axis 35. The swivelling of the lever 33, 34 causes a displacing of the slide 33 on the guide track 39 until the notch 40 at its front end, in collaboration with the notched holders 47 and part 49, hold a part of the edge frame 51 and the end winding of the spring 52 firmly. With further movement of the lever 21 the roller 30 runs on a curved part of the lever arm 33, concentric with the axis 19, so that the pressing of the slide 33 remains constant.

By the engaging of a coupling (not shown), the toothed wheel 5 is now turned in the direction of the arrow (Figs. 1-3), the cams 3 and 4 on the shaft 2 and the toothed wheels 6 and 41 then also turning. The lever 8 first of all slides off the nose 3' of cam 3 and swings under the action of gravity round the pin 9, whereby the finger 10 comes to lie with its end on the wire 26, clamping the wire firmly against a part 10' of the machine stand 1 so that it can no longer be pushed further forwards or drawn back during the binding operation.

The operator 46 (Fig. 7) on the bearing bush 45 of the toothed wheel 41 now winds the pushed-forward piece of wire in screwed windings W round the edge frame 51 and the wire of the end ring of the spring 52. As soon as the nose on the cam 4 swings the roller 11 out on the arm 12, the knife 16 on the arm 13 moves downwards and, in collaboration with the counter-knife 18, severs the wire close to the winding W. At the same time the hollow 17 on the back of the knife 16 presses the end of the severed wire close against the edge frame and the end winding, and the connection is completed. The parts of the appliance then return to their initial positions as shown in Fig. 1 and the completed connection may be removed from the machine.

What I claim is:

1. Apparatus for joining the end rings of helical springs to the frame of spring boxes for the manufacture of upholstered articles, comprising a rotatable wire winding member adapted to receive parts of said frame and said ring, clamping means for non-rotatably holding said frame and said ring with their parts to be joined lying in juxtaposition inside said rotatable wire winding member, feeding means for feeding a binding wire piecemeal to said wire winding member from a wire stock, means for rotating said wire winding member, said member thereby winding the wire piece fed thereto in screw-like convolutions around said frame and ring parts inserted therein, second clamping means for firmly gripping the wire behind the end piece thereof

fed to said winding member, and cutting means for severing said wound wire piece from the wire stock, said cutting means having a stationary knife and a movable knife cooperating therewith, said movable knife being provided at its side opposite said winding member with a hollow shoulder fitting the contour of the windings, said shoulder pressing the cut-off end of said wire piece against the joined parts upon the operation of said movable knife.

2. Apparatus for joining the end rings of helical springs to the frame of spring boxes for the manufacture of upholstered articles, comprising a rotatably mounted wire winding member provided with a toothed portion, with an eccentrically axially extending projection on one side and with a radial slot allowing said frame and ring parts to be inserted into said winding member to a position substantially along the axis of the latter, clamping means for rotatably holding said frame and ring parts in that position consisting of two spaced stationary jaw members situated at both sides and near the axis of said winding member and two slidably mounted jaw members cooperating with said stationary jaw members, a slidably mounted clamping member for piecemeal advancing the end of a binding wire from a wire stock to said winding member placing an end piece of said wire under the action of said projection, said clamping member gripping the wire when moving toward said winding member and loosely sliding along said wire when moving in the opposite direction, a pivotally mounted clamping member adapted to grip the wire to prevent it from moving backwards, a second pivotally mounted clamping member adapted to grip the wire to prevent it from moving forward during the operation of said winding member and having an extended lever arm, lever means for moving said slideable jaw members to their clamping position and for moving said slideable clamping means to advance said wire when the frame and ring parts have been inserted in said slot, toothed gearing means engaging said toothed portion of said winding member for rotating the latter, said projection on said winding member thereby engaging said advanced wire end piece to wind it around said frame and ring parts, cutting means for severing said wound wire piece from the wire stock and consisting of a stationary knife and a movable knife fixed to one end of a pivotally mounted lever, a cam follower on the other end of said lever, a cam wheel driven by said gearing means and cooperating with said cam follower to operate said cutting means when the wire piece has been wound, and a second cam wheel driven by said gearing means and cooperating with said extending lever arm on said second pivotally mounted clamping member to move said clamping member away from the wire to allow the advancing of said wire after the operation of said winding member.

3. Apparatus for joining the end rings of helical springs to the frame of spring boxes for the manufacture of upholstered articles, comprising a cylindrical wire winding member having an axial hole, a radial slot leading to said hole, said member further being provided with a toothed portion and with an axially extending eccentric finger-like projection on one side, said winding member being rotatably mounted in bearings having a radial slot, said two radial slots in said winding member and said bearings allowing said frame and ring parts to be inserted in juxtaposition into said hole, clamping means for

non-rotatably holding said frame and ring parts in that position, means for advancing a binding wire piecemeal from a wire stock to said winding member placing an end piece of said wire under the action of said finger-like projection, said wire being advanced along a line at an oblique angle with the axis of said winding member, clamping means for fixedly holding the wire during the operation of said winding member, toothed gearing means engaging said toothed portion of said winding member for rotating the latter, said finger-like projection on said winding member thereby engaging said advanced wire piece to wind it in screw-like convolutions around said frame and ring parts, and cutting means for severing said wound wire piece from the wire stock, said cutting means having a stationary knife and a movable knife cooperating therewith, said movable knife being provided at its side opposite said winding member with a hollow shoulder fitting the contour of the windings, said shoulder pressing the cut-off end of said wire piece against the joined parts upon the operation of said movable knife.
